UNITED STATES PATENT OFFICE.

HUGO HAEFNER, OF NEWARK, NEW JERSEY; MICHAEL BUCKLER, ADMINISTRATOR OF SAID HAEFNER, DECEASED, ASSIGNOR, BY DIRECT AND MESNE ASSIGNMENTS, TO ADAM OHL, OF SAME PLACE.

VARNISHING-MACHINE.

SPECIFICATION forming part of Letters Patent No. 495,484, dated April 18, 1893.

Application filed March 26, 1892. Serial No. 426,476. (No model.)

To all whom it may concern:

Be it known that I, HUGO HAEFNER, a citizen of the United States, residing at Newark, in the county of Essex and State of New Jersey, have invented certain new and useful Improvements in Varnishing-Machines; and I do hereby declare the following to be a full, clear, and exact description of the invention, such as will enable others skilled in the art to which it applies to make and use the same, reference being had to the accompanying drawings, and to letters of reference marked thereon, which form a part of this specification.

The purpose of this invention is to provide an improved machine for varnishing or painting tin or other material, which is of simple construction and which will apply the coats of varnish or paint to the material to be varnished without necessitating any special

preparation, and avoiding all waste.

The invention is further designed to more evenly distribute the daub or paint over the surface of the material, such as sheet tin, to treat the same so that it is under the perfect control of the operator, to cut the sheet tin into pieces of the proper size and to punch the same and to so handle the sheet metal pieces that they are discharged in a finished condition from the machine ready to be laid out for drying.

The invention therefore consists of certain novel arrangements and combinations of parts, such as will be hereinafter more fully described and finally embodied in the clauses of the claim.

In the accompanying sheets of drawings, in which is illustrated a machine adapted to carry out the principles of my invention, Figure 1 is a plan view of the said machine. Fig. 2 is a vertical longitudinal section of the same taken on line α , showing the supporting frame and the bearings for the several distributing rolls in side elevation. Figs. 3 and 4 are the two side elevations of the machine, and Fig. 5 is a vertical section of the machine taken on the central longitudinal axis thereof in the plan in Fig. 1. Fig. 6 is an enlarged view of the cutter and punching rolls shown, partly in section and partly in elevation, and Fig. 7 is a vertical section of the same taken on line

γ in Fig. 6. Fig. 8 is a plan view of the parts comprising a scraper employed in connection with the machine. Fig. 9 is an end view of the same, and Fig. 10 is a section of the same taken on line α in Fig. 8.

55

Similar letters of reference are employed in each of the above described views to indicate corresponding parts.

In said above described views, a indicates a suitable varnish or paint holding tank, which as shown in Fig. 5, is preferably provided with a sloping portion a' , which acts to direct the surface daub back into the tank. Said tank or vat a is suitably secured between two standards or supporting frames b and b' of the machine to which is secured at the opposite end of the machine any suitable form of arms or brackets b^2 and b^3 on which is arranged a tilting table b^4 .

As will be seen from Figs. 1, 3 and 4, the drive-shaft c , which may be arranged in adjustable bearings b^5 in the two frames b and b' is provided on the one end with a driving pulley c' and on its opposite free end with a gear c^2 which meshes with a pinion d arranged to rotate on the side of the one frame, as shown in said Fig. 4. Meshing with said pinion d is a gear d' and meshing with said gear d' is a second gear d^2 , connected with axles d^3 and d^4 respectively and on which are arranged

75

the feed rolls d^5 and d^6 respectively, as clearly shown in Figs. 1 and 5. Said shafts or axles d^3 and d^4 may be arranged in adjustable boxes in said frames b and b' , and on said axles I can arrange shearing or punching devices, as will be more fully described hereinafter. On said shaft c between the two frames b and b' , is arranged a carrying off roll C of metal and directly above the same, and in line with the vertical axis of said roll C is a paint or varnish feeding roll E arranged on a shaft e provided with a gear e' which meshes with a gear c^3 on the drive shaft c . Said roll E is preferably made of caoutchouc and the shaft e arranged in suitable bearings b^6 in the sides of the frames b and b' . Meshing with said gear e' on the shaft e is another gear-wheel f' on a shaft or axle f for driving a second caoutchouc roll F also arranged in adjustable bearings b^7 , which bearings are capable of an up and down movement.

and down movement, as well as an adjustment to either side, as will be clearly seen from Figs. 2 and 4. And finally, meshing with the gear f' is a gear g' on an axle g , provided with paint or varnish distributing roll G , which roll extends down into the tank or vat below the surface of the paint or varnish therein, as will be evident from Fig. 5.

I have found by practical demonstration that it is of great advantage to have all rolls of the same diameter and that they must have the same surface speed and therefore I have represented the gears c^3 , c^4 , e' , f' and g' all of the same size, but the diameters of the several feed rolls and the size of said gears may be varied if necessary.

The operation of the machine is as follows:— The power-shaft c , by means of the intermediate arranged system of gearing causes the feeding or pinching rolls d^3 and d^4 to rotate in the direction of arrows, as indicated in Fig. 5, and rolls C , E , F and G rotate in the direction of the arrows, as indicated in said figure. The sheets of tin, or other material to be varnished are placed upon the table b^4 and inserted in front of the pinching rolls d^3 and d^4 from which they are fed between the carrying-off roll C and the feed roll E upon the carrying-off apron h , as will be seen from Fig. 5. Said apron is arranged on an axle h' having a pulley h^2 and operated by a belt h^3 from a driving pulley c^4 on the shaft c . When the several rolls or cylinders are thus operated and rotate as indicated, in the direction of the arrows in Fig. 5, the paint or varnish is carried up from the tank or vat a and evenly spread over its periphery by means of an adjustable scraper i which can be adjusted to permit a substantially thick or thin coating of paint or varnish on the surface of the roll, and this paint or varnish is then distributed by contact to the gum roll F and from this roll to the other gum roll E and thereby spread upon the sheet tin or other material passed between the rolls E and C . Said roll C has in contact therewith an adjustable scraper j secured between the frames b and b' , the scraping surface of which removes any paint or varnish that may have been brought upon the surface of the roll C and causes the paint or varnish to fall into a suitable receptacle j' , as shown in Fig. 5. It will be noticed that all the rolls except the roll G are arranged in adjustable bearings, whereby they can be brought farther apart or in very close proximity according to the thickness of the coat of paint or varnish to be applied to the material passing over the roll C .

As will be seen more especially from Figs. 9 and 10, the adjustable scraper consists essentially of a plate i' to which the scraper i is secured. Said plate i' is arranged on an adjustable bearing plate i^2 , all of which are arranged on brackets b^8 on the frames b and b' by means of the plates b^9 and the bolts b^{10} . Said plates i' and the bearing plate i^2 are adjustably held together by means of the bolts

i^3 which pass through elongated openings or holes in said plates, as illustrated in Fig. 10.

Near the front edge of the plate i' I have arranged a series of screw threaded holes i^4 , in which are placed thumb screws i^5 by means of which the scraper i , which is made of spring metal can be tightly forced against the surface of the roll or relaxed therefrom to cause a uniform thick or thin coating of paint or varnish to be distributed on the cylindrical surface of the roll G , as the case may be.

As hereinbefore stated, in place of the rolls d^3 and d^4 , I may provide said axles or shafts d^3 and d^4 , with cutters or shearing washers and punching devices, as shown in Figs. 6 and 7. In said construction, the shaft d^3 is provided at one end with a screw-thread d^7 and the shaft d^4 with a similarly arranged screw-thread d^8 . These shafts or axles are arranged in their bearings in the frames b and b' in the manner described herein above but are provided with collars k and k' of which the upper collar k' is slightly longer than the collar k . Said collars abut against the inner edges of the bearings in the frame of the machine and adjacent to said collars I arrange the cutters l on the shaft d^3 and the cutters l' on the upper-shaft d^4 respectively, and then a suitable number of plain washers or collars m , when another set of cutters can be arranged on the shafts, which are also held in place by collars or washers m , and, on the screw-threaded ends of the shafts may be another set of cutters which are held in place by suitable nuts n and n' arranged on the screw-threaded ends of the shafts. Thus it will be seen, that any such number of shears or cutters can be suitably arranged on the axles or shafts, the intermediately arranged plain washers or collars acting as straightening rolls for flattening out the sheet metal and conducting it to the rolls C and E when the sheets are painted or varnished and delivered upon the carrying-off apron.

From Figs. 6 and 7, it will be seen that one or all the cutters on the upper shaft d^4 may be provided with suitably arranged punching fingers l^2 , which project beyond the peripheral surface of the roll, and are adapted to force themselves through the tin and pass into the perforations o' in a collar o on the opposite shaft d^4 . The construction of said collars o will be seen from the two sectional views of said collars, in Figs. 6 and 7. Said collars are provided with an annular chamber o^2 formed by the walls o^3 and o^4 , see Fig. 6, and in these chambers I arrange a suitable number of spring-actuated guides o^5 , each provided with one or more fingers o^6 which extend into said perforations o' , as clearly indicated in Fig. 7. Now, when the sheet metal passes between the two punching collars, the small pieces of metal will accumulate upon said fingers o^6 and be retained in said perforations until the perforation reaches the lowest point during the revolution of the shaft d^4 , and the metal pieces will then be forced from the perfora-

tions o' by the spring-actuated guides o^5 and drop beneath the machine, as will be clearly understood. These forms of rolls d^5 and d^6 are of great advantage in cutting the sheet metal into pieces of the proper size and perforating the same when used for trunk tin, said holes being used for the reception of nails for securing the tin to the trunk body.

The primary advantage of my invention, and also the principal object is to avoid any double handling of the sheet metal pieces, by cutting the same and punching them and also providing the pieces with the proper coating of paint or varnish. It is this feature of my invention which I wish to claim broadly and which I deem of special importance. It not only reduces the time and labor involved in applying the varnish, but every part of the sheet metal, on its face, is painted or varnished with equal facility and no waste is caused by the cutting of the same into sheets of the proper size.

The apron, for carrying off the finished pieces, may be made of canvas or any other suitable material.

Having thus described my invention, what I claim is—

1. In a machine for coating sheet metal or other articles with paint or varnish, the combination, of a varnish or paint holding tank of the form herein specified, a roll G arranged

in said tank, a daub conveying roll F in contact with said roll G, and a pair of rolls E and C, one above the other, through which the sheet to be coated or painted is passed, an apron arranged behind said roll C, a scraper in contact with said roll G, and a scraper in contact with said roll C, a pair of feeding rolls d^5 and d^6 , a system of gearing for operating said rolls, a pulley c^4 and a pulley h^2 and belt h^3 for operating said conveyer, all of said parts being arranged substantially as and for the purposes set forth.

2. In a machine for coating sheet metal or other articles with paint or varnish, the combination with an axle d^4 cutters l' provided with punching pins l^2 and washers m , thereon and an axle d^3 cutters l and collars o having perforations o' , spring-actuated guides o^5 and pins o^6 , arranged in a chamber o^2 in such collars o , of paint or varnish distributing rolls, a paint or varnish tank, and actuating devices for causing the rotation of said rolls, for the purposes set forth.

In testimony that I claim the invention set forth above I have hereunto set my hand this 14th day of March, 1892.

HUGO HAEFNER.

Correction in Letters Patent No. 495,484.

It is hereby certified that the name of the administrator in Letters Patent No. 495,484, granted April 18, 1893, upon the application of Hugo Haefner, of Newark, New Jersey, for an improvement in "Varnishing-Machines," was erroneously written and printed "Michael Buckler," whereas said name should have been written and printed *Michael Buehler*; and that the said Letters Patent should be read with this correction therein that the same may conform to the record of the case in the Patent Office.

Signed, countersigned, and sealed this 9th day of May, A. D. 1893.

[SEAL.]

JNO. M. REYNOLDS,
Assistant Secretary of the Interior.

Countersigned:

JOHN S. SEYMOUR,
Commissioner of Patents.
